FIG. 7.

INVENTOR.

Lionel Moses
and Joseph A. Miller
ATTORNEY.

UNITED STATES PATENT OFFICE.

LIONEL MOSES, OF PROVIDENCE, RHODE ISLAND.

DEVICE FOR HAMMERING SILVER.

1,409,230.

Specification of Letters Patent. Patented Mar. 14, 1922.

Application filed April 21, 1920. Serial No. 375,587.

To all whom it may concern:

Be it known that I, LIONEL MOSES, a citizen of the United States, residing at Providence, in the county of Providence and State 5 of Rhode Island, have invented new and useful Improvements in Devices for Hammering Silver, of which the following is a specification.

This invention relates to devices for hammering silver and pertains more particularly to a hammer for producing what is commonly termed hammered silver, i. e., silver showing hammer marks.

The primary object of the invention is to 15 provide a device of this kind which will hammer the silver by use of power as distinguished from the customary method of hammering manually or by hand.

The invention aims to provide a device of 20 this kind which is positive in action; which enables various forms of hammer heads to be substituted at will in an easy and quick manner, and which also is adjustable to vary the action of the hammer head, namely to 25 strike a light or a heavy or hard blow to the silver.

Further and other objects will be later set forth and manifested in the course of the following description.

30 In the drawings:

Fig. 1, is a longitudinal section view of the invention;

Fig. 2, is a detail side elevation of the striker;

35 Fig. 3, is an end view of a modified form of hammer head;

Fig. 4, is a detail view of the cam, in side elevation;

Fig. 5, is a section on line 5—5 of Fig. 1,

40 Fig. 6, is a detail view of the fastening collar for the hammer head or end.

Figure 7, is a transverse section taken through nut 12 and sleeve 13.

In proceeding in accordance with the 45 present invention, a flexible drive shaft 1, is employed which can be rotated through suitable power of any type. A cam plate 2, is connected to the shaft 1, so as to be rotated thereby, and engages the head 3, of a striker

50 4. A guide member 5, is secured to the striker 4, by means of a cross-pin 6, the guide 5, operating between tracks 7, carried by a shank 8, the latter being partly enclosed by a sleeve 9, to which sleeve it is secured by a screw 10. The cam plate 2 is mounted

in a housing 20, the latter having the upper ends of the tracks 7 suitably secured thereto.

The lower end of the striker 4, is guided in the shank 8, as depicted in Fig. 1, the striker being tensioned by a coil spring 11, which abuts the guide 5, the latter therefore affording an abutment for the spring, and an adjusting nut 12 mounted on striker 4, and between the tracks 7, being held by the latter against rotation but capable of longitudinal sliding movement therealong. For this purpose the tracks 7 are slotted at 21 to receive the threaded wings 22 of the nut 12. A knurled sleeve 13 threadedly engages about the nut wings 22 and by turning the sleeve, the nut 12 may be moved along the tracks so as to vary the tension of the spring 11, and thereby the blow of the striker, as is obvious. A spring 14, is disposed between the tracks and sleeve 9, so as to bear against the sleeve 13, and thus hold the latter against accidental movement.

A collar 15, slotted at 16', is threaded onto the lower end of the shank 8, and engages about the hammer 16, the latter having a head 17, and an intermediate cross-pin 18, the slot enabling the collar to be disengaged from the hammer upon unthreading of the collar from the shank and then lateral movement of the collar to cause pin 18 of the hammer to move through the slot 16', to thereby allow a hammer with a different type of head 17', such for instance as shown in Fig. 3, to be substituted.

In operation, it will be seen that the rotation of cam 2, will effect reciprocation of the striker 4, the action being dependent upon the tension to which spring 11, is adjusted by rotation of sleeve 13. The striker will impact against hammer 16, and the latter will in turn strike blows on and against the silver. The hammer is freely mounted in the shank 8, and its reciprocal movements are limited by the lower end of the shank and by the collar 15, as is obvious, due to 100 the presence of the pin 18.

Having thus described my invention, what I claim as new and desire to secure by Letters Patent is:—

1. In combination with a casing, a rotat- 105 ing cam therein, and means to rotate same, a striker having a head engageable by the cam so as to be actuated thereby, a guide borne by the striker, tracks for the guide, an adjustable member mounted over the 110

- striker, a spring between the member and guide so as to have its tension adjusted by the adjustment of the member, a hammer engageable with the striker, a cross-pin borne by the hammer, and means engageable with the cross-pin to secure the hammer removably in place.
2. In a device of the type set forth, a casing, a striker movable therein, a nut adjustable on the striker, means rotatably encircling the casing and connected to the nut to adjust the latter, a guide on the lower end part of the striker engaging the interior of the casing, a spring encircling the striker and engaged between the nut and guide, a hammer slideable in the casing, and means to actuate the striker.
3. In a hammer of the type described, a casing, a hammer having a shank slideable through the outer end of the casing, means to strike the hammer intermittent blows, a member rigidly carried by the hammer shank and engageable with the outer end of the casing to limit movement of the hammer in one direction, and a member on the casing and formed to receive said first member therein and to engage the latter to limit movement of the hammer in the opposite direction.
4. In combination with a casing and an operating cam therein, a striker having a head on one end engageable with the cam so as to be reciprocated thereby, an adjustable nut disposed between the striker ends and through which the striker is movable, an abutment on the striker, a spring surrounding the striker and disposed between the abutment and nut, means for sliding the nut so as to adjust the spring tension, and a hammer engageable with the striker.
5. In combination with a casing, a striker therein, and means to actuate same, a shank through which the striker passes, a hammer slideable in the shank and having a cross-pin movable below the shank, the striker being engageable with the hammer to actuate the latter, and a collar on the shank engageable with and for limiting movement of the cross-pin, the collar having a slot to allow same to be disengaged from the hammer by passing of the cross-pin through the slot.
6. In combination with an operating cam and a striker actuated thereby, a spring for tensioning the striker, a slideable nut for adjustably tensioning the spring, a sleeve threaded on the nut for sliding the latter, and a hammer operated by the striker.
7. In a silver hammering device, a casing, a reciprocable striker therein, a rotatable cam for actuating same in one direction, spring means for tensioning the striker, means rotatably encircling the casing for adjusting the tension of the spring means exteriorly of the casing, and a hammer actuated by the striker.
8. In a hammer of the type described, a casing, a hammer therein, spring tensioned means to strike the hammer intermittent blows, means to adjust the tension of the spring, and a rotatable member encircling the casing for operating said adjusting means of the spring.

In testimony whereof I have signed my name to this specification in the presence of two subscribing witnesses.

LIONEL MOSES.
